CLAIM

The ornamental design for a medicine injector, as shown and described.

DESCRIPTION

FIG. 1 is a perspective view of a medicine injector showing my new design;

FIG. 2 is a perspective view thereof;

FIG. 3 is a top view thereof;

FIG. 4 is a left side view thereof;

FIG. 5 is a right side view thereof;

FIG. 6 is a rear view thereof; and,

FIG. 7 is a front view thereof.

The broken lines showing in the Figures are included for the purpose of illustrating portions of the medicine injector that form no part of the claimed design.

1 Claim, 6 Drawing Sheets
